DESIGN FOR A COMPRESSED AIR DISPENSING CASING

Joseph C. Woodford, Wayne, Pa., assignor to
John Wood Manufacturing Company, Inc.,
Conshohocken, Pa., a corporation of Delaware

Application February 16, 1938, Serial No. 75,174

Term of patent 14 years

To all whom it may concern:

Be it known that I, Joseph C. Woodford, a citizen of the United States, residing at Wayne, in the county of Montgomery and State of Pennsylvania, have invented a new, original, and ornamental Design for Compressed Air Dispensing Casings, of which the following is a specification, reference being had to the accompanying drawing, forming part thereof.

In said drawing; Fig. I is a front elevational view of a compressed air dispensing casing, showing my new design. Fig. II is a plan view of said casing. Fig. III is a side elevational view thereof.

I claim:

The ornamental design for a compressed air dispensing casing, as shown.

JOSEPH C. WOODFORD.
